UNITED STATES PATENT OFFICE.

SAMUEL W. RUSHMORE, OF PLAINFIELD, NEW JERSEY.

COOLING SYSTEM.

Application filed October 27, 1924. Serial No. 746,022.

The present invention relates to a cooling system of the general character disclosed in my prior Patent No. 1,378,724, granted May 17, 1921. In cooling systems of this type, the 5 water circulation from the cooling jacket of the engine is short circuited through the lower chamber of a radiator below the cooling tubes or "honey-comb" thereof, so that the latter operates as an upflow steam condenser. Proper and substantially constant 10 boiling temperatures are soon reached because there is very little cooling until the boiling point is reached. The cooling is by evolution of steam in the engine jacket and in the lower chamber of the radiator, causing 15 upflow of the steam into the restricted passages of the honey-comb where it is cooled, and the condensate flows down in close heat exchange relation to the rising steam so that it returns to the circulation at practically 20 the same temperature as the water from which it was boiled off.

Even so, the time required for the initial heating to boiling temperature is considerable 25 because in the system of my said patent, as in any other system where a continuous forced circulation of cooling water is maintained through the cylinder jacket, the jacket water cannot reach any steady maximum 30 temperature condition until all the water circulating in the system has been heated to said temperature.

Hence an important feature of the present invention involves further reduction of 35 the time required to reach boiling point, by short circuiting the water circulation through a short, low resistance path, thus permitting the water to remain in the jacket, substantially unaffected by the continuous circulation 40 in the cooling system. Thus the effect of the heat generated in the engine is concentrated on the relatively small amount of water in the jacket and brings it quickly to boiling. Thus I obviate heating all of the 45 water in the system, as has heretofore been necessary, in order to raise the jacket water temperature. I am thus able to raise the jacket water to optimum temperature in a few minutes.

50 In connection with this short circuited water circulation, I prefer to employ baffle members in the upper end of the cylinder jacket, said members forming a chamber affording a short, low resistance path through 55 which the short circuiting of water takes place. The chamber is in communication

with the main body of water in the jacket through relatively restricted openings so that when steam evolution occurs, the circulation may be automatically extended 60 throughout the entire body of water in the jacket.

While this method of rendering temperature of the jacket water substantially independent of the temperature of the water in 65 the cooling system, constitutes an important improvement of the system of my prior patent, it is even more useful for any system where there is likely to be too much cooling of the circulating water. A further feature 70 of the invention includes a water jacket around the oil pan of the crank case through which the hot jacket water from the engine circulating system is caused to flow, thereby maintaining the crank case oil at relatively 75 high temperature. This oil pan jacket preferably serves as a reserve supply tank for the entire system and it is into this jacket that water from the lower radiator tank is 80 delivered. Water from the oil pan jacket is 80 pumped into the cylinder jacket by any convenient type of circulating pump.

While the water in the cylinder jacket is being heated, cold water is circulated through the oil pan jacket and the lower 85 chamber of the upflow steam condenser. A substantial amount of the steam which is first evolved in the cylinder jacket is used to heat this water so that before any substantial steam evolution can occur in the 90 radiator, the water in the cylinder will be boiling and the water in the oil pan jacket will have nearly reached boiling temperature.

When the water in both jackets has become 95 heated to the desired temperature and steam evolution and condensation takes place in the radiator, I may prevent the loss of water which may be forced up the condensing tubes and into the top of the radiator above the 100 "honey-comb" by an arrangement similar to that shown in my copending application, Ser. No. 746,023, filed on even date herewith. Such an arrangement involves the use of a drain pipe for permitting the return to the 105 system of water forced into the upper chamber of the radiator. This drain pipe prevents back pressure in the condenser and in fact maintains a substantially uniform condenser pressure and has the further advantage that it permits the use of the cheapest and most efficient types of radiator core 110

construction with passages too small or too narrow for the free return of the condensate against the upflowing stream. In accordance with the preferred embodiment of the invention, the drain pipe communicates with the drain from the lower tank of the radiator back to the oil pan jacket and if desired, the latter pipe may be provided with a restricted orifice therein which predetermines the rate of gravitational flow from the lower radiator chamber to the oil pan jacket and prevents the possibility of back pressure blocking up the drain from the top of the radiator.

In accordance with another feature of the invention, the circulating pump which takes water from the oil pan jacket and delivers it under pressure to the cylinder jacket is driven by vertical shaft run through a tube which communicates from the atmosphere to a point above the oil level in the engine crank case, which serves also as an improved breather tube to permit the discharge of gas and vapors from the crank case to a point below where they will be swept away under the car instead of being discharged in the usual way under the engine hood and through the unavoidable openings in the floor into the passenger space of the car. I thus take advantage of conventional engine construction and eliminate the necessity for making extensive alterations in the crank case casting and avoid the necessity of stuffing box to prevent escape of oil. If desired, the oil pan jacket may be heat insulated so that when the engine is idle the crank case oil will in large measure be prevented from becoming cold and viscous. Features of minor importance are the provision of means in connection with the engine jacket for preventing a flow of water down the inlet pipe when the engine is stopped and for preventing jacket water from spilling out of the outlet pipe when descending a steep grade.

The invention may be better understood from the following description in connection with the accompanying drawings, wherein

Fig. 1 is a view partly in section and partly in side elevation of an internal combustion engine equipped with the cooling system;

Fig. 2 is fragmentary front elevation of the upper end of the cylinder jacket.

The circulating system for cooling water, as illustrated in the drawings, includes a jacketed cylinder head 10 delivering water from its upper forward end through a pipe 11 to a tank or chamber 12 in the bottom of a radiator which includes upflow steam condensing pipes 13 of relatively restricted cross section communicating at their upper ends with a tank or header 14. From the tank 12, water passes by gravity through a pipe 15 into an oil pan jacket 16 enclosing preferably the entire oil pan of the crank case. From jacket 16 water is withdrawn through

a pipe 17 by a circulating pump 18 and passed upwardly through a pipe 19 back to the cylinder head jacket 10. The jacket space of cylinder head 10 communicates with the jacket space surrounding the cylinders below, through the usual openings 10^b. I preferably employ a vertical baffle 10^c extending across the cylinder head 10 near the front end thereof formed with openings 10^d and defining a relatively small chamber 20 offering a low resistance path through which short circuiting of water occurs prior to the time that the stagnant water in the jacket reaches the boiling point. Pipe 11 is connected by a short section of flexible hose 21 to an inverted U-shaped pipe 22 forming part of a casting 23 bolted over an opening 24 in chamber 20 to provide an outlet opening for escaping steam and water. By providing the U-bend in the pipe 22 and raising the intermediate portion of the bend above the top of the water jacket there is no danger of water gravitationally running from the jacket down to the lower end of the radiator when the car is descending a steep grade. The lower end of pipe 11 is connected through a flexible pipe section 25 with the inlet pipe 26 which enters the lower radiator tank.

Inasmuch as it is desired to have the inlet and outlet from chamber 20 as close together as possible, I may run the pipe 19 directly into a nipple 27 forming part of casting 23 and communicating with an inlet pipe 28 running through the outlet opening 24. The delivery end of pipe 28 is turned up as at 29 to deliver water near the top of the jacket. The shape of the pipe 29 is intended to prevent jacket water from gravitationally running back to and through the pump when the engine is stopped.

The circulating pump 18 is preferably disposed below the oil pan jacket and is driven by a vertical shaft 30 which extends through a vertical crank case breather tube 31. This tube permits gases from the crank case to escape and be carried off under the car without being trapped under the hood from whence they are likely to leak through the floor into the car.

Shaft 30 may be driven by a gear 31 operating from horizontal worm shaft 32 or in any other convenient or conventional manner.

By virtue of the construction above described, it will be seen that when operation of the engine is started and the circulating pump begins to work, there will be a short circulation of water from the discharge end 29 of the pipe 19 directly to the pipe 22 and back through pipe 11 to the lower end of the radiator. Water from the tank 12 drains through a restricted orifice 34 down to the oil pan jacket. The water in the cylinder jacket 10 will remain substantially stagnant until the time when boiling begins. In other

words, the jacket water will heat up rapidly while a circulation of cold water is being maintained through tank 12, jacket 16, and chamber 20. As steam begins to be evolved 5 in the jacket 10, the circulation of water in the jacket will gradually become more general and the steam and hot water escaping through the outlet pipe 22 will heat the excess water circulating through the tank 12 10 and oil pan jacket. Before the water which is delivered from pipe 11 into tank 12 is sufficiently hot to effect any appreciable steam evolution in the tank, the water in the oil pan jacket will have nearly reached boiling point. When the water in both jackets 15 has reached maximum or desired temperature and steam evolution and condensation is occurring in the regular way in the radiator or condenser, a certain amount of water or condensate may be forced or blown up through the restricted tubes 13 into the header 14 at the top of the radiator. This water, however, cannot result in any substantial back pressure within the radiator 20 and will not be blown out through the conventional safety valve because I provide a drain pipe 35 into which it overflows as soon as it reaches the upper header 14. Pipe 35 25 drains into the pipe 15 at a point below the orifice 34 and since the amount of water which can pass from tank 12 through this orifice is considerably less than the pipe 15 is capable of taking care of, there will be no substantial back pressure in the pipe 35. In 30 fact, there is more likely to be a subnormal pressure in this pipe which will actually suck water out of the top of the radiator and reduce and equalize pressures throughout the entire radiator condenser.

40 In order to prevent the crank case oil from becoming chilled and consequently viscous and sluggish when the engine is temporarily stopped, I encase the oil pan jacket with a sheathing of heat insulating material 36 so that the heat from the water in this jacket 45 may be conserved as long as possible to prevent the temperature of the crank case oil from falling to an undesirably low point.

The short circuiting of water from the 50 inlet and outlet of the cylinder jacket is of considerable importance and possesses numerous advantages entirely independently of whether or not the oil pan jacket is used. It is of additional importance, however, 55 where the oil pan jacket is used since it permits the use of the additional heating jacket without in any way retarding the heating of the cylinder jacket water. The baffle 10°, while assisting materially in providing an 60 efficient short circuit, is not essential to successful operation, since if the inlet and outlet to and from the cylinder jacket be properly arranged in close proximity to each other to provide a low resistance flow path, a short circuit will be established irrespec-

tive of whether or not the water is delivered into a baffled chamber. The arrangement for driving the pump is very convenient when the system is installed in cars provided with a crank case breather tube such as the tube 70 21, but it will be evident that other expedients might be resorted to for driving the pump without affecting the efficiency of operation of the cooling system. While the oil pan jacket preferably completely encloses and 75 surrounds the oil pan, it may, if desired, merely be used for surrounding the usual sump in the bottom of the crank case.

I claim:

1. A cooling system for internal combustion engines, comprising a force feed water circulating system of small heat dissipating capacity, serially including a water jacket, a high level overflow outlet from said jacket, 80 a small capacity water container to which said outlet is connected, large capacity heat dissipating passages extending upward above the container, operating as an upflow condenser, interposed between the container and an upper outlet for the escape of air, steam or water, a relatively high resistance conduit leading from said water container to pumping means for force feeding water from said conduit into the water jacket, in combination with a relatively low resistance 85 conduit from near the top of the upflow condenser passages to the intake of the pumping means, thereby affording a normally open, low resistance path for the escaping water to flow to said intake in parallel with water flowing through the higher resistance circuit.

2. A cooling system operating by the boiling and condensing method, having a circulating system, including a jacketed element to be cooled, a radiator having a lower water chamber through which the cooling medium is short-circuited and a plurality of upflow condensing passages above said chamber, means for withdrawing water from the chamber and delivering it to the jacket, in combination with means including a conduit providing short-circuited water circulation, from a point near the top of the jacket but below the level of overflow to the radiator, to the return part of the circuit leading 100 to the water jacket.

3. A cooling system operating by the boiling and condensing method, having a circulating system, including a jacketed element to be cooled, a radiator having a lower water chamber through which the cooling medium is short-circuited and a plurality of upflow condensing passages above said chamber, an inlet in the jacket through which water is delivered from the tank and an outlet in the 115 jacket from which water flows to the tank, said inlet and outlet being relatively close together to afford a low resistance short-circuited path for the flow of water through 120 the jacket.

4. A cooling system operating by the boiling and condensing method, including a jacketed element to be cooled, an upflow steam condenser, means for short-circuiting the cooling medium through the lower end of the condenser and means for short-circuiting the cooling medium through means in communication with the upper end of the jacket.
5. In a cooling system for internal combustion engines, an engine jacket having inlet and outlet ports for cooling fluid, arranged in close proximity to each other, an air cooled radiator having a lower chamber to which said outlet port is directly connected so that the radiator operates as an upflow condenser, and means for conveying the cooling fluid from said lower chamber to said inlet port.
6. In a cooling system for internal combustion engines, a cylinder jacket having inlet and outlet ports for cooling fluid, arranged in close proximity to each other, and to the topmost level of the water in the jacket, an air cooled radiator having a lower chamber to which said outlet port is directly connected so that the radiator operates as an upflow condenser, and means for conveying the cooling fluid from said lower chamber to said inlet port.
7. In a cooling system for internal combustion engines, a cylinder jacket having inlet and outlet ports for cooling fluid, arranged at approximately the same level, an air cooled radiator having a lower chamber to which said outlet port is directly connected so that the radiator operates as an upflow condenser, and means for conveying the cooling fluid from said lower chamber to said inlet port.
8. In a cooling system for internal combustion engines, an engine jacket having a chamber in its upper end communicating with the body of the jacket only through restricted openings, and inlet and outlet pipes for cooling fluid both opening into the chamber, said chamber offering a low resistance flow path through which cooling medium is short-circuited while the cooling medium in the body of the jacket is being raised to a temperature sufficient to cause thermo-circulation through said restricted openings.
9. In a cooling system for internal combustion engines, a cylinder jacket having a chamber in its upper forward end separated by a partition and communicating with the body of the jacket only through restricted openings in said partition, and inlet and outlet pipes for cooling fluid opening into the chamber, said chamber offering a low resistance flow path through which cooling medium may be short-circuited while the cooling medium in the body of the jacket is being raised to a temperature sufficient to cause inflow of cool fluid into the jacket through some of said restricted openings and outflow of heated fluid through others of said openings.
10. A cooling system for internal combustion engines, including a jacketed element to be cooled, a heat radiating element to which cooling medium is passed from the jacket and from which cooling medium is returned to the jacket, the inlet and outlet passages to and from the jacket being disposed one within the other.
11. A cooling system operating by the boiling and condensing method having a circulating system including a jacketed element to be cooled, a radiator having a lower water chamber through which the liquid portion of the cooling medium is short-circuited, and a plurality of condensing passages above said chamber, a jacketed element to be heated, means for passing cooling medium successively through the jacketed element to be cooled, the lower chamber of the radiator and the jacketed element to be heated and means providing a low resistance short-circuited path for the cooling medium through the jacketed element to be cooled.
12. A cooling system operating by the boiling and condensing method, having a circulating system including a cylinder jacket, a radiator having a lower water chamber through which the cooling medium is short-circuited, and a plurality of upflow condensing passages above said chamber, an oil pan jacket into which water flows from the chamber and a pump for returning the water from the oil pan jacket to the cylinder jacket.
13. A cooling system operating by the boiling and condensing method, having a circulating system including a cylinder jacket, a radiator having a lower water chamber through which the cooling medium is short-circuited, and a plurality of upflow condensing passages above said chamber, an oil container jacket into which water flows from the chamber and a pump for returning the water from the oil container jacket to the cylinder jacket, and means providing a low resistance short-circuited path for the cooling medium through the cylinder jacket.
14. A device of the class described in claim 13, wherein a restricted orifice regulates the gravitational flow of water from the lower radiator tank to the oil pan jacket.
15. A device of the class described in claim 13, wherein the oil container is enclosed by a covering of heat insulating material.
16. A cooling system operating by the boiling and condensing method, having a circulating system including a cylinder jacket, a radiator having a lower water chamber through which the cooling medium

is short-circuited and a plurality of upflow condensing passages above said chamber, said passages communicating with a header at the upper end of the radiator, an oil container jacket into which water from the lower end of the radiator gravitationally flows, means for returning water from the oil container jacket to the cylinder jacket, and means for draining water blown up the tubes into the header back to the circulating system.

17. A cooling system operating by the boiling and condensing method, having a circulating system including a cylinder jacket, a radiator having a lower water chamber through which the cooling medium is short-circuited and a plurality of upflow condensing passages above said chamber, said passages communicating with a header at the upper end of the radiator, an oil container jacket into which water from the lower end of the radiator gravitationally flows, means for returning water from the oil container jacket to the cylinder jacket, and means for draining water blown up the tubes into the header, including a drain pipe

connecting the header with the circulating line from the lower radiator tank to the oil container jacket.

18. A device of the class described in claim 16 wherein the circulating line from the lower tank to the oil pan jacket includes a restricted portion limiting the rate of flow therethrough and wherein the drain pipe delivers into said circulating pipe below said restricted portion.

19. A cooling system, including in a closed circulating system, a cylinder jacket, a radiator, an oil container jacket and a circulating pump, the inlet and outlet from the cylinder jacket being arranged in close proximity to each other.

20. A cooling system, including in a closed circuit a cylinder jacket, a radiator, an oil container jacket and a pump, said oil container jacket being adapted to receive water draining from the radiator and being covered with heat insulating material.

Signed at Plainfield in the county of Union and State of New Jersey, this 25th day of October, A. D. 1924.

SAMUEL W. RUSHMORE.
